UNITED STATES PATENT OFFICE

JACOB TELLER AND ARTHUR P. SCHULZ, OF NEW YORK, N. Y., ASSIGNORS TO TELLER CORPORATION, OF CHATTANOOGA, TENNESSEE, A CORPORATION OF TENNESSEE

DESIGN FOR A TABLE-TOP, STRAIGHT-LINE GAS OR ELECTRIC RANGE

Application filed September 10, 1931. Serial No. 41,063. Term of patent 7 years.

To all whom it may concern:

Be it known that we, JACOB TELLER and ARTHUR P. SCHULZ, citizens of the United States, and residents of New York city, in the county of New York and State of New York, have invented a new, original, and ornamental Design for a Table-Top, Straight-Line Gas or Electric Range, of which the following is a specification, reference being had to the accompanying drawings, forming a part thereof.

Figure 1 is a perspective view of the range; and

Figure 2 is a similar view of the upper portion thereof with the doors in open position.

We claim:—

The ornamental design for a table-top, straight-line gas or electric range, as shown.

JACOB TELLER.
ARTHUR P. SCHULZ.
